UNITED STATES PATENT OFFICE.

ERNEST A. COSTAIN, OF NEW YORK, N. Y., ASSIGNOR TO THE HARTFORD CARPET COMPANY, OF HARTFORD, CONNECTICUT.

DESIGN FOR A CARPET.

SPECIFICATION forming part of Design No. 14,467, dated December 11, 1883.

Application filed July 28, 1883. Term of patent 3½ years.

To all whom it may concern:

Be it known that I, ERNEST A. COSTAIN, of New York city, New York, have invented a new and original Design for Carpets, of which the following is a specification, reference being had to the accompanying photograph, which forms a part of the same.

The invention relates to a design to be worked into or upon surfaces—such as carpets or similar fabrics; and it consists in the novel configuration and grouping of figures, herein specifically shown and claimed.

The accompanying photograph is a face view of a carpet showing my new design.

15 The design consists of several leaf and flower groups on a plain ground.

A is a large group of leaves and flowers, massed together over a large portion of the

design, having fern and blossom-sprays jutting out on all sides. B is a smaller group of 20 leaves and flowers, also massed centrally, and having blossom and leaf sprays projecting out on all sides. Other smaller groups complete the design.

I claim—

1. The design for a carpet, consisting of the group A, substantially as shown and described.
2. The design for a carpet, consisting of the group B, substantially as shown and described.
3. The design for a carpet, consisting of the 30 groups A and B, and the other groups, substantially as shown and described.

ERNEST A. COSTAIN.
